UNITED STATES PATENT OFFICE.

WILLIAM S. EVANS, OF ORRVILLE, OHIO.

IMPROVEMENT IN PIANO-LEG PROTECTORS.

Specification forming part of Letters Patent No. **179,690**, dated July 11, 1876; application filed May 24, 1876.

To all whom it may concern:

Be it known that I, WILLIAM S. EVANS, of Orrville, Wayne county, State of Ohio, have invented certain Improvements in Piano-Leg Protectors, of which the following is a specification:

The object of my invention is to provide protectors for piano-legs, which may be readily adjusted and detached as required, for cleaning and polishing piano-legs.

The majority of pianos in use have their legs tied up in newspapers or cloth, presenting an unsightly appearance and hiding from view the most elaborately-designed part of the instrument.

My invention consists in constructing protectors for the piano-legs, of wire, willow-ware, cane, or other suitable material, which will effectually protect the exposed or front part of the legs, at the same time exposing the leg to view. These protectors are fastened to the under side of the piano-case in such a manner that they fit around the front part of the leg, the lower part of the protectors resting on the floor, thereby giving them stability and stiffness to thoroughly protect the leg from injury, and at the same time allow the beauty of the finished carving and polishing to be seen.

In order to more fully describe my invention I refer to the accompanying drawings, forming a part of this specification.

Figure I represents a side view of my improved protector for piano-legs. Fig. II is a plan view of the same.

A represents the frame, to which is fastened the wire net-work *a a*. *b* is a spiral wire wound around the upper part of the frame A, giving elasticity to this part of the frame, which touches the under side of the piano-case, when the protector is adjusted or detached. *c* is another spiral wire wound around the lower part of the frame A, giving elasticity to this part of the frame which rests on the floor. *d* is an eye made in the end of the upper part of frame A, for the purpose of fastening the protector to a hook applied to the bottom part of the piano-frame. *e* is a vertical bend of the opposite end of the frame A, fitting into a mortise or journal in the bottom of the piano-frame, allowing the protector to be swung out from the leg when it is desired to clean or polish the same.

Having thus described my invention, I desire to claim—

As a new article of manufacture, a piano-leg protector, consisting of frame A with net-work *a*, elastic bands *b* and *c*, and eye *d*, and hook *e*, substantially as described.

WILLIAM S. EVANS.
